UNITED STATES PATENT OFFICE.

WILLIAM H. HORN, OF POLLOCK, SOUTH DAKOTA.

COTTER-PIN REMOVER.

Application filed June 20, 1923. Serial No. 646,646.

To all whom it may concern:

Be it known that I, WILLIAM H. HORN, a citizen of the United States, residing at Pollock, in the county of Campbell and State of South Dakota, have invented certain new and useful Improvements in Cotter-Pin Removers, of which the following is a specification.

This invention relates to tools for use in extracting cotter pins. It frequently happens that cotter pins which require to be extracted are found to be so located that they cannot be reached by ordinary tools or, if reached, sufficient pulling force cannot be exerted to extract the pins. The present invention, therefore, aims to provide a tool which may be employed under the conditions above recited as well as under more favorable conditions, and which will permit of cotter pins being extracted with ease where ordinarily considerable labor and time would be consumed in accomplishing this result.

In the accompanying drawings:

Figure 1 is a vertical longitudinal sectional view through a cotter pin extracting tool embodying the invention;

Figure 2 is a view in side elevation of the tool;

Figure 3 is a detail transverse sectional view on the line 3-3 of Figure 1 looking in the direction indicated by the arrows.

The tool embodying the invention comprises a shank which is indicated by the numeral 1 and which at one end is threaded as indicated by the numeral 2. A handle 3 of wood or any other suitable material is provided with a bore 4 of a diameter to fit the shank, and the handle is fitted upon the threaded end of the shank and constitutes a hand grip by grasping which the tool may be held in one hand in proper engagement with the cotter pin to be removed. A nut 5 is threaded onto the portion 2 of the shank 1 and bears against the inner or lower end of the handle 3, the nut being adjustable upon the said threaded portion of the shank. A second nut 7 is threaded onto the threaded extremity of the shank and bears against a washer 8 which in turn bears against the opposite or outer end of the handle 3.

The numeral 9 indicates a hammer member comprising a sleeve-like body 10 having a bore 11 which is smooth and slidably receives the said shank 1. The hammer member 9 is therefore freely slidable upon the shank 1 of the tool and its movement is

limited in one direction upon said shank 1 by means of a key or taper pin 12 or any other element suitable for the purpose, the key or other element being driven transversely through the shank 1, as clearly shown in Figure 1 of the drawings.

The opposite end of the shank 1 is reduced in diameter and threaded as indicated by the numeral 13, and this end of the said shank is fitted into a threaded socket 20 formed in an extracting head 21 which is in this manner associated with the said shank. The extracting head 21 is provided with two prongs one indicated by the numeral 22 and the other by the numeral 23. The prong 22 is curved laterally obtusely to the axis of the shank 1 and is gradually tapered from its inner to its outer end, the said prong being of substantially circular contour in cross section throughout its length. The other prong, 23, is likewise curved laterally but substantially to hook form, it being therefore substantially in the form of a hook having a pointed entering end 24 presented substantially in the direction of the handle end of the shank. As compared with the contour of this prong, it will be noted by reference to Figure 1 of the drawings, that the pointed end of the prong 22, which end is indicated by the numeral 25, is presented at an angle away from the reduced end or forward end of the shank.

In the use of the tool embodying the invention, the pointed end 25 of the prong 22 is worked into the head of the cotter pin to suitably open or expand the same, if this should be found desirable or necessary, and after this has been done the pointed end 24 of the prong 23 is hooked into the eye of the pin, and, with the handle 3 gripped in one hand, the other hand is employed to sharply slide the hammer member 9 rearwardly upon the shank 1 to deliver an impact against the nut 5 and thus transmit a sudden pulling force to the cotter pin for the purpose of extracting the same.

It will further be observed that the pointed end 25 of the prong 22 projects beyond the foremost part of the prong 23 so that the said prong 22 may be worked into the eye of the cotter pin without any interference on the part of the prong 23 by reason of said prong 23 coming into contact with any adjacent part. It will also be noted that by removably fitting the head 21 onto the reduced end 13 of the shank 1,

and by employing the key or taper pin 12 as an abutment for the hammer member 9, the head 21 may be readily removed and a new or different shaped head substituted therefor, and likewise by removing the said head and the pin 12, the member 9 may be removed from the shank. Also it will be evident that the nut 5 or any equivalent part of the handle securing means, and the 10 taper pin or key 12 constitute spaced abutments upon the shank between which the hammer member is disposed and slidably movable.

Having thus described the invention, what is claimed as new is:

1. A cotter pin remover comprising a shank, a hammer slidably mounted upon the shank, and a head detachably secured to one end of the shank and provided with spaced 20 diverging prongs, one of which is hooked-shape and constitutes an extracting prong, the other prong being disposed substantially in the longitudinal plane of the shank and

provided with a pointed terminal deflected laterally with respect to the shank and constituting an expanding prong.

2. A cotter pin remover comprising a shank having one end thereof provided with a reduced threaded extension, a handle fixed to the opposite end of the shank, a hammer member slidably mounted on the shank between the threaded extension and handle, and a detachable head having a threaded socket formed therein adapted to receive the threaded extension of the shank and provided at one side with a hooked-extracting prong curving laterally and having its entering end presented substantially in the direction of the handle and at its opposite side with a tapered expanding prong disposed substantially in the longitudinal plane of the shank with its entering end pointed and deflected laterally away from the first-mentioned prong.

In testimony whereof I affix my signature.
WILLIAM H. HORN. [L.S.]
